UNITED STATES PATENT OFFICE.

FREDERICK WILLIAM MAGEE, OF LONDON, ONTARIO, CANADA, ASSIGNOR OF ONE-HALF TO THOMAS WILLIAM BAKER, OF LONDON, ONTARIO, CANADA.

MOTORIST'S EYE SHIELD.

Application filed August 20, 1928. Serial No. 300,889.

My invention relates to improvements in motorists' eye shields of the type disclosed in my Canadian Patent #268,313 dated February 8, 1927, and my United States Patent #1,659,324, dated February 14th, 1928, and the object of the present invention is to provide resilient means extending between the head and the hat worn thereon which will not be hard and rigid and confined to small pressure area and thereby become uncomfortable after continued use, by which the shield may be adjusted vertically and held in any position to which it is adjusted so that the lower edge of the shield will be opposite the direct line of vision of the wearer, by which a shield may be held from lateral movement so that the shield perforations through which vision is obtained are retained definitely in proper position in front of the eye to have clear vision therethrough and at the same time provide a supporting device which may be folded directly beneath the shield body so as to be compact and easily insertable if desired in the vest pocket of the wearer, and it consists essentially of the arrangement and construction of parts as hereinafter more particularly explained.

Fig. 1 is a sectional view through my eye shield and showing it applied to the head of the wearer of the hat.

Fig. 2 is a perspective view of my eye shield showing it in the position indicated in Figure 1 and the shield partially broken away for the purpose of exhibiting the construction.

Fig. 3 is a similar view to Fig. 2 showing the shield folded.

Fig. 4 is an enlarged sectional view through my eye shield in the operative position.

Fig. 5 is a similar view to Figure 4 in the folded position.

In the drawings like characters of reference indicate corresponding parts in each figure.

1 indicates the body of the eye shield which is formed of thin metal or other suitable opaque material, the lower edge 1* of which is intended when adjusted to be opposite the central line of vision of the wearer.

2 are perforations formed in the shield body adjacent the edge 1 and one end of the shield and through which the adjacent eye

of the wearer has vision. The opposite end of the eye shield is cut away preferably in an inclined direction as indicated at 3.

4 is a retainer, the retainer 4 extends inwardly at right angles to the body of the eye shield and is located centrally thereof opposite the nose of the wearer and forms a recess into which the nose fits so as to prevent any lateral movement of the shield body. The shield body is in no way supported by the retainer 4 which only serves to prevent lateral movement as above set forth.

The upper edge of the shield body is provided at its centre with an inwardly extending tongue 5 which is bent back upon itself to form a bearing sleeve 6, the free edge of the tongue being riveted or otherwise secured to the body thereof as indicated at 7.

8 is a rectangular member preferably formed of wire, the lower end of which is swung in the bearing sleeve 6. The parallel downwardly extending portions of the member 8 forms slideways upon which a transverse member 9 is slidably mounted. The member 9 is provided with an upwardly extending tongue 10 of thin sheet springing material which is bent back upon itself as indicated at 11 to form an outwardly extending resilient inclined portion 12.

When the shield is to be worn the members 8 and 9 are in the position shown in Figure 2 and are placed against the forehead of the wearer, the hat 13 is then placed upon the wearer's head compressing the spring portions of the tongue 10 together so as to exert a binding action against the inner face and the surface of the head and thereby prevent vertical movement.

The member 9 may be slid to any desired position upon the member 8 so as to suit various types of heads and so that it will be comfortable for all proportions and shapes of heads. By this construction a retainer is provided which will positively hold the shield in any position to which it is vertically adjusted with a pressure, which will be soft and cushioned and which will present a relatively broad bearing surface against the head which will not be uncomfortable to the wearer.

When the shield is in operative position the member 4 forms a notch into which the nose fits and prevents any lateral movement of the shield and yet at the same time will

not prevent of its vertical adjustment and further when the head is tilted slightly forward in such a position a motorist would naturally assume when looking at the mechanism of his engine will allow of the shield swinging slightly away from the face of the wearer so that it will not obstruct the view of such mechanism and will automatically return itself to position when the wearer assumes the normal position and at the same time the member 4 definitely holds the perforations 2 and the cut away portion 3 in the right position required for clear vision when a motorist is approaching the glaring head lights of another car.

When the device is not in use the member 9 may be slid towards the inner end of the member 8 so that it will not project beyond the end of such member, and the member 8 20 may be folded back against the under face of the shield body and at each side of the side portions of the member 4 in the position shown in Figure 2 so that the shield may be slipped longitudinally in the upper vest pocket of the wearer and thereby be conveniently carried.

From this description it will be seen that I have devised an eye shield adapted for use by motorists which will prevent head light glare and yet allow clear vision of the roadway on the opposite or outer side of the car, the light glare being prevented by the solid shield which extends in front of the eyes of the wearer so that powerful light rays will not impinge against the eyes and yet allow of clear view of an approaching car through the perforated portion of the shield and at the same time provide a shield of this type the lower edge of which may be readily adjusted to any desired position in relation to the eyes of the wearer and held in such position either from vertical or lateral movement and at the same time provide a means for holding the shield in position which will be comfortable and not dig into

the flesh of the wearer's forehead, and to further provide a shield which may be folded into compact form so that it may be readily slipped into the upper vest pocket of the wearer.

It may be pointed out that the inturned portion 5 at the top edge of the shield body is for the purpose that in the position the shield hangs of throwing the lower edge of the shield in towards the nose. If the top 55 of the nose were straight with the forehead it would be of no advantage, but as the nose is usually formed with a hollow portion at the top thereof the shade body will by reason of this offset portion sit more firmly 60 against the nose.

What I claim as my invention is:—

1. In a motorist's eye shield, a shield body, a rectangular member hingedly mounted to the upper edge of the shield body and forming parallel guides, a member slidably upon such guides, and a resilient compressible portion carried by such slidably member to bear against the inner surface of the wearer's hat. 65

2. In a motorist's eye shield, a shield body, 70 a rectangular member hingedly mounted to the upper edge of the shield body and forming parallel guides, a member slidably upon such guides, a tongue extending upwards from the slidable member and bent outwardly upon itself in V-form to bear against the inner face of the wearer's hat. 75

3. In a motorist's eye shield, the combination with a shield body having a tongue extending inwardly at its upper edge and 80 forming a bearing sleeve extending parallel therewith, a rectangular loop swung at its lower end in such sleeve, a slidable member suitably carried upon the side portions of the loop, a tongue extending upwardly 85 therefrom and bent back upon itself in V-form to resiliently bear against the inner face of the hat of the wearer.

FREDERICK W. MAGEE.
